Design No 645.

Hugh Rock's Ornamental Design for a Hair Brush.

Patented May 2nd 1854

Fig. 1.

Fig. 2.

Fig. 3.

UNITED STATES PATENT OFFICE.

HUGH ROCK, OF BOSTON, MASSACHUSETTS, ASSIGNOR TO H. ROCK AND FRANCIS McLAUGHLIN.

DESIGN FOR THE FRAMES AND HANDLES OF HAIR-BRUSHES.

Specification forming part of Design No. 645, dated May 1, 1854.

To all whom it may concern:

Be it known that I, HUGH ROCK, of Boston, in the county of Suffolk and State of Massachusetts, have invented or produced a new and ornamental Design for a Hair-Brush; and I do hereby declare that the same is represented in the accompanying drawings.

In the said drawings, Figure 1 denotes a top view of a hair-brush constructed in accordance with my ornamental design. Fig. 2 is a side view of it. Fig. 3 is a vertical, central, and longitudinal section of it.

In producing my said design I have had in view the making of a hair-brush with a metallic frame or handle, it being cast or founded according to the design or pattern in question.

The said design is composed in part of an elliptical annulus A, having its upper edge or surface scalloped or convoluted, as seen at a, and its lower edge denticulated, as seen at b b. Such design is also composed in part of

an open handle B, of the form seen in the drawings, and united to the annulus A, the ornament at the union being two leaves c c, branching asunder and united on the annulus by a chain of semi-ellipsoidal gutta or drops. Into the annulus part of the handle the brush-block C is inserted and fixed by closing the dents or teeth down upon its sides, a cover or name-plate D being previously placed over it.

I claim—

The ornamental design, substantially as above described and as exhibited in the drawings.

In testimony whereof I have hereunto set my signature the 25th day of March, A. D. 1854.

HUGH ROCK.
